US00D955988S

(12) **United States Design Patent** (10) **Patent No.:** **US D955,988 S**
Li (45) **Date of Patent:** **** Jun. 28, 2022**

(54) **HYDROGEN GENERATOR**

(71) Applicant: **Guangzhou Jeudao Household Electric Appliance Co., Ltd.,**
Guangdong (CN)

(72) Inventor: **Changshan Li**, Guangdong (CN)

(73) Assignee: **Guangzhou Jeudao Household Electric Appliance Co., Ltd.,**
Guangdong (CN)

(**) Term: **15 Years**

(21) Appl. No.: **29/757,301**

(22) Filed: **Nov. 5, 2020**

(30) **Foreign Application Priority Data**

Jun. 2, 2020 (CN) 202030269247.X

(51) LOC (13) Cl. **13-01**

(52) U.S. Cl.

(57) **CLAIM**

The ornamental design for a hydrogen generator, as shown and described.

DESCRIPTION

FIG. 1 is a perspective view of a hydrogen generator showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

(Continued)

The broken line portions of the hydrogen generator in FIGS. 1-7 represent unclaimed portions of the claimed design and form no part thereof.

1 Claim, 6 Drawing Sheets
